UNITED STATES PATENT OFFICE.

CHARLES H. WARREN, OF ATLANTA, GEORGIA, ASSIGNOR TO DRAPER CORPORATION,
OF HOPEDALE, MASSACHUSETTS, A CORPORATION OF MAINE.

FILLING-REPLENISHING LOOM.

1,322,851.

Specification of Letters Patent. Patented Nov. 25, 1919.

Application filed April 28, 1919. Serial No. 293,135.

To all whom it may concern:

Be it known that I, CHARLES H. WARREN, a citizen of the United States, and a resident of Atlanta, in the county of Fulton and State of Georgia, have invented an Improvement in Filling-Replenishing Looms, of which the following description, in connection with the accompanying drawings, is a specification, like characters on the drawings

10 representing like parts.

This invention relates to filling replenishing looms and more particularly to the means for withdrawing filling from the shuttle eye after a replenishing operation.

15 In looms of this general type, it is common to provide means for parting or cutting the filling between the cloth selvage and the outgoing filling carrier or bobbin on call for replenishment of filling, and if the end of the 20 filling leading from the discharged filling carrier or bobbin is not withdrawn from the shuttle eye, it is liable to be caught and carried into the shed.

Numerous devices have been devised having for their object the accomplishment of the above purpose and some of them have effectively performed the desired function. The present invention has for its object to improve devices for withdrawing the filling 30 end from the shuttle eye following the replenishing operation and to provide means to effectively accomplish this purpose, such means being simple in construction, effective in operation, and readily applicable to 35 looms of this type now in general use.

Various features of the invention will best be made clear from the following description and accompanying drawings of one good form of mechanical means for carrying 40 the invention into practical effect.

In the drawings:

Figure 1 is a perspective view at the replenishing side of a filling replenishing loom, some of the parts being broken away 45 for the purpose of clearness of illustration;

Fig. 2 is a similar view with some of the parts omitted and showing the loom elements and associated features in another position.

50 In the drawings the loom frame is shown as of the usual type having secured thereto the stand 1 carrying the hopper 2 in which are contained the loaded filling carriers 3.

Pivottally mounted as usual on the stand 1 is the transfferer 4 which serves to eject the 55 filling carrier or bobbin to be discharged, and place in the shuttle another filling carrier or bobbin with a fresh supply of filling thereon. The transfferer may be appropriately operated, as well understood by 60 those skilled in the art, and further description thereof appears unnecessary.

The lay 5, the shuttle box 6, the picker-stick 7, and shuttle 8, are or may be of any desired and well known character of construction.

Many of the devices heretofore provided for withdrawing the filling end leading from the discharged filling carrier to the shuttle eye, have been of complicated character requiring undesirable additions to or auxiliary movements associated with the other loom parts, but in the present invention one of the important features consists in the simple means employed for effecting 75 the withdrawal of the end of the filling from the shuttle eye without adding materially to the loom parts or the auxiliary operation of associated elements.

Secured to the loom frame in any appropriate manner is the bobbin chute 9, which may be of any suitable character for directing the filling carriers or bobbins as they are discharged from the shuttle into the receptacle or can 10. In the present instance the bobbin chute 9 is formed of sheet metal or other suitable material and is connected to the loom frame by means of a bracket 11 to which the rear portion of the bobbin chute is connected, as indicated in 90 Fig. 1.

In the present instance of the invention, the bobbin chute 9 is provided with a slot 12 leading from its outer edge, portion inwardly toward the loom frame and the 95 upper wall 13 of the slot thus formed, is provided with a series of roughened edge portions or teeth 14, the construction being such that should the filling between the discharged filling carrier or bobbin 15 and the 100 shuttle eye be engaged by the roughened edge or toothed portion 14, projecting downwardly from the upper edge of the slot 12, it will be held by these teeth as the shuttle is picked and thus cause the filling end to 105 be drawn from the shuttle eye if it has not

already been drawn therefrom by the primary operation of the device, as will presently appear.

- 5 Mounted on the lay or movable therewith is a thread catcher or finger 16. In the present instance, the thread catcher or finger 16 is secured to the picker-stick guide 17 by means of a bolt 18 and such thread catcher or finger 16 is outwardly bent so 10 that when a filling carrier or bobbin is discharged from the shuttle on call for replenishment of filling, such outgoing filling carrier or bobbin may pass rearwardly of the thread catcher or finger 16.
- 15 The thread catcher or finger 16 is located relatively to the slot 12 in the bobbin chute 9 so that on each beat up movement of the lay the thread catcher 16 will pass through the slot 12 to a position frontwardly of the 20 bobbin chute. When replenishment of filling is effected, the outgoing filling carrier is discharged from the shuttle when the lay is in substantially its frontward position, and consequently the thread catcher 16 is in its 25 position frontwardly of the bobbin chute 9, the relation of parts being such that the discharged filling carrier or bobbin 15, in passing from the shuttle and over the bobbin chute 9, will pass over the slot 12 in the 30 bobbin chute and between it and the thread catcher or finger 16.

As the lay retreats after the filling replenishing operation, the filling *a* which has thus been laid between the thread catcher 35 16 and the slot 12 in the bobbin chute, as indicated in Fig. 1, will be caught by the finger or thread catcher 16 as the lay retreats and a bight of the filling thread will be drawn rearwardly through the slot 12 of the bobbin chute, substantially as indicated 40 in Fig. 2. The effect of this is to draw upon the filling thread between the discharged filling carrier or bobbin 15 and the eye of the shuttle, with the result that the filling 45 thread will be withdrawn from the eye of the shuttle by the increased length of thread caused by the thread catcher forming the bight of the filling, as indicated at *b*, Fig. 2. When the filling thread is thus drawn rear- 50 wardly through the slot 12 of the bobbin chute by the thread catcher or finger 16, the part thereof leading upwardly to the shuttle eye will be engaged by one of the teeth or roughened edge portions 14 at the 55 lower edge of the upper wall 13 of the slot 12, so that should the end of the filling not have been wholly withdrawn from the shuttle eye by the backward movement of the thread catcher or finger 16, as described, 60 the teeth 14 on the lower edge of the upper wall 13 of the slot, will securely hold the filling as the shuttle is picked after the replenishing operation, thereby insuring the withdrawal of the filling thread from the 65 shuttle eye and obviate all possibility of

the end of the filling being carried into the shed.

As hereinbefore described, the bobbin chute 9 is secured in fixed position to the loom frame, consequently the arm or upper portion 13, provided with the teeth 14 extending downwardly, is a fixture relative to the loom frame, and when formed by slotting the bobbin chute as at 12, no additional part or movement is required for this portion of the thread withdrawing device.

The thread catcher 16 may be formed as an outwardly bowed or bent or cast finger, preferably so curved at its end portion as to retain the bight of the filling *b* and prevent it slipping off the end of the finger as the lay goes back after a replenishing operation. The device is simple, effective, and may readily be applied to any of the so-called automatic looms now in use, without material change or additions thereto.

Claims:

1. In a filling replenishing loom, the combination of a bobbin chute mounted in fixed position on the loom frame and provided with a slot extending in a generally horizontal direction longitudinally of the chute, downwardly extending teeth formed on the upper wall of the slot, a thread catcher secured to the picker stick guide 90 below the shuttle box and formed to pass through said slot in the chute to a position in front thereof as the lay beats up to permit a bobbin to pass between it and the chute as it is discharged from the shuttle 100 and adapted on the backward movement of the lay to carry a bight of filling thread rearwardly through said slot and withdraw the filling thread from the shuttle.

2. In a filling replenishing loom, the combination of a bobbin chute mounted in fixed position on the loom frame and provided with a slot extending in a generally horizontal direction longitudinally of the chute, a thread catcher mounted on the lay to pass 110 through said slot in the chute to a position in front thereof that a bobbin may pass between the catcher and chute when discharged from the shuttle and lay the thread between the bobbin and shuttle over said 115 slot, said catcher being adapted on the rearward movement of the lay to carry a bight of the filling thread rearwardly through said slot.

3. In a filling replenishing loom, the combination of a chute for filling carriers provided with a slot over which the filling carrier passes when discharged from the shuttle, a thread catcher mounted on the lay to pass through said slot to a position front- 120 ward of the bobbin chute as the lay beats up to permit the discharged filling carrier to pass between the catcher and chute and adapted on the backward movement of the lay to form a bight in the filling over the 125 130

upper and lower edges of the slot in the chute between the discharged carrier and shuttle and withdraw the filling from the shuttle.

- 5 4. In a filling replenishing loom, the combination of a chute for directing filling carriers discharged from the shuttle and provided with a slot, a thread catcher that is movable with the lay and passes through 10 said slot in the chute to a position in front thereof as the lay beats up to permit the filling to be laid across said slot in rear of the thread catcher when the filling carrier is discharged from the shuttle and adapted by 15 the rearward movement of the lay to drag the filling through the slot in the chute and about the upper and lower edge thereof to form a bight in the filling extending through the slot.
- 20 5. In a filling replenishing loom, the combination of a bobbin chute to direct filling carriers as they are discharged from the shuttle and provided with a slot, a finger secured to the lay to pass through said slot 25 to a position frontward thereof as the lay beats up and adapted on its rearward movement to engage the filling leading from a discharged bobbin and withdraw the filling end rearwardly through the slot and from 30 the shuttle.
6. In a filling replenishing loom, the combination of a bobbin chute having a slot extending in a direction transversely of the loom, one of the walls of which is provided 35 with teeth, and a thread catcher for engaging the filling thread leading from a dis-

charged bobbin in front of the chute and carrying a bight of the filling thread through the slot in the bobbin chute.

7. In a filling replenishing loom, the combination of a bobbin chute having a slot extending from one edge in a direction transversely of the loom, a thread catcher, and means for causing the thread catcher to engage the filling thread leading from a discharged bobbin to the shuttle in front of 45 said slot and carry a bight of the filling thread rearwardly through said slot.

8. In a filling replenishing loom, the combination of a bobbin chute provided with a 50 serrated edge portion below its upper edge, a finger mounted on the lay for movement frontwardly and rearwardly of said serrated edge portion by reciprocation of the lay to engage the filling leading from a discharged bobbin to the shuttle frontwardly 55 of said serrated edge and carry a bight of filling rearwardly below and across said edge.

9. In a filling replenishing loom, the combination of a clearer member, means for securing the clearer member in fixed position on the loom frame to permit a filling carrier to pass frontwardly thereof on replenishment of filling, and a thread catcher mounted 60 on the lay to engage the filling frontwardly of the fixed clearer and draw the filling about the fixed clearer as the lay goes back.

In testimony whereof, I have signed my 70 name to this specification.

CHARLES H. WARREN.
